George A. Johnson
BY Geo. J. Haight

ATTORNEY

UNITED STATES PATENT OFFICE.

GEORGE A. JOHNSON, OF CHICAGO, ILLINOIS, ASSIGNOR TO WILLIAM H. MINER, OF CHAZY, NEW YORK.

DRAFT-RIGGING.

1,300,403.

Specification of Letters Patent. Patented Apr. 15, 1919.

Application filed January 8, 1918. Serial No. 210,865.

To all whom it may concern:

Be it known that I, GEORGE A. JOHNSON, a citizen of the United States, residing at Chicago, in the county of Cook and State of Illinois, have invented a certain new and useful Improvement in Draft-Rigging, of which the following is a full, clear, concise, and exact description, reference being had to the accompanying drawings, forming a part 10 of this specification.

This invention relates to improvements in draft riggings.

The object of the invention is to provide a relatively inexpensive, compact shock absorbing mechanism, more particularly adapted for railway cars and which is composed of few parts and wherein the use of stop castings is avoided.

In the drawing forming a part of this 20 specification, Figure 1 is a longitudinal, vertical, sectional view of a portion of a draft rigging showing my improvements in connection therewith. Fig. 2 is a horizontal, sectional view taken substantially on the 25 line 2—2 of Fig. 1. And Fig. 3 is a transverse, vertical, sectional view taken substantially on the line 3—3 of Fig. 1.

In said drawing 10—10 denote channel shaped center or draft sills of a railway car 30 arranged in the ordinary manner and to the inner faces of which may be secured plain reinforcing plates 11—11 where the draft gear is to be located. The improved draft gear, as shown, preferably embodies four 35 transversely arranged removable keys 12, 13, 14 and 15 mounted in suitable slots cut in the plates 11 and sills 10. All of said keys 12, 13, 14 and 15 are stationary and adapted to act as stops for the gear. Located between the two sets of keys 12 and 13, and 40 14 and 15, are spring followers 16 and 17. Said followers 16 and 17 are provided with marginal flanges 18 on their inner faces to thereby provide suitable sockets or recesses 45 to receive the ends of vertical, twin arranged springs 19—19 and hold the latter in position. A combined spring spacer and limiting stop 20 is preferably interposed between the springs.

50 The front set of keys 14 and 15 are spaced vertically a proper distance to receive the butt 21 of a draw bar so that the lower key 15 supports the draw bar butt and the latter

is guided between both keys 14 and 15. The rear set of keys 12 and 13 are so spaced as 55 to receive and guide the rear end of a horizontal yoke 22 which is connected to the coupler by a key 23. To support and guide the followers, the rear follower 17 is provided with rearwardly extended horizontal 60 flanges 24—24 slidably engaging the upper and lower surfaces of the keys 12 and 13, respectively, and the front follower 16 is provided with similar forwardly extended horizontal flanges 25—25 engaging the upper and lower surfaces of the keys 14 and 15, respectively. The rear follower 17 may also be provided with a central rearward extension 26 which slides between the keys 12 and 13. 70

As will be apparent from the preceding description, the followers are supported by the keys as well as limited in their movements thereby. This eliminates the necessity of supporting or saddle plates for any 75 of the parts inasmuch as the springs are in turn carried by the followers 16 and 17. The arrangement is very compact, is inexpensive and avoids the use of the usual shouleder stop castings while at the same time 80 providing for the necessary capacity for a spring type of gear although the invention may be employed with other types of cushioning mediums. 85

I claim:

1. In a draft rigging, the combination with draft sills, of a front set of vertically spaced transversely extending keys mounted in said sills, a draw bar having the butt thereof supported by and guided between 90 said keys, a rear set of vertically spaced transversely extending keys mounted in said sills, a horizontal yoke connected to said draw bar having the rear end thereof supported and guided by said keys, followers interposed between said keys, integral means on said followers coöperable with the respective sets of keys and by which said followers are supported and guided, and cushioning means between the followers. 95 100

2. In a draft rigging, the combination with draft sills, of a front set of vertically spaced transversely extending keys mounted in said sills, a draw bar having the butt thereof supported by and guided between 105 said keys, a rear set of vertically spaced

transversely extending keys mounted in said sills, a horizontal yoke connected to said draw bar having the rear end thereof supported and guided by said keys, followers 5 interposed between said keys, and cushioning means between the followers, each of said followers having horizontally extending

flanges slidably engaging the upper and lower surfaces of the upper and lower keys respectively of the corresponding set of keys. 10

In witness that I claim the foregoing I have hereunto subscribed my name this 29th day of Dec. 1917.

GEORGE A. JOHNSON.
